UNITED STATES PATENT OFFICE.

LOUIS PAULERO, OF PETERSBURG, VIRGINIA, ASSIGNOR TO AMERICAN ELECTRIC TOOL COMPANY, INCORPORATED, OF PETERSBURG, VIRGINIA, A CORPORATION OF VIRGINIA.

CALKING-TOOL.

1,358,326.

Specification of Letters Patent.

Patented Nov. 9, 1920.

Application filed July 17, 1918. Serial No. 245,382.

To all whom it may concern:

Be it known that I, LOUIS PAULERO, a citizen of the United States, and a resident of Petersburg, in the county of Dinwiddie and State of Virginia, have invented certain new and useful Improvements in Calking-Tools, of which the following is a specification.

My invention relates to improvements in calking tools, and it consists in the constructions, combinations and arrangements herein described and claimed.

An object of my invention is to provide a tool for calking seams and more particularly the seams of wooden vessels, wherein the oakum or other calking material is mechanically manipulated to form a loop or tuck in the oakum strand precisely as is done when the oakum is manually introduced beneath the calking iron.

Another object of the invention is to provide a calking tool having a positively operated tucking mechanism which is so adjusted as to render it sensitive to varying seam widths, consequently forming tucks of corresponding sizes, precisely as is done by the finger of the hand when the oakum strand and the seam are under manual observation.

A further object of the invention is to provide a calking tool wherein the oakum strand is automatically fed and the tuck is automatically formed, by a direct and positive mechanical action from the calking iron.

A further object of the invention is to provide a novel resilient support for the hammer support and the calking iron.

Other objects and advantages will appear in the following specification, reference being had to the accompanying drawings, in which:

Figure 1 is a vertical section of the improved calking tool,

Fig. 2 is a detail front elevation of the calking tool showing the tucker arms and side oakum feeder,

Fig. 3 is a diagrammatic sectional view showing the formed tuck about to be driven into the seam,

Fig. 4 is an inverted plan view of the tucking blade,

Fig. 5 is a side elevation showing the side oakum feeder,

Fig. 6 is a diagrammatic sectional view illustrating the formation of a relatively large tuck for a wide seam,

Fig. 7 is a diagrammatic sectional view illustrating the formation of a relatively small tuck for a narrow seam,

Fig. 8 is a cross section of the rear axle of the calking tool carriage, and

Fig. 9 is a vertical section of a modification of the calking tool.

The subject matter of the present invention is an improvement over my co-pending applications for calking tools #1 and #2, respectively filed on January 16, 1918, Serial No. 212,127, and May 6, 1918, Serial No. 232,925. The novelty in the present invention lies more particularly in the peculiar tucking mechanism. It has been demonstrated in actual practice, that a long period of training is required before a man can skilfully form the tuck in an oakum strand so as to accommodate the varying widths of seams along the side of a vessel.

Obviously it requires a practised eye, as well as finger, to loop the strand over far enough to form a tuck of the required size, so that when it is driven into the seam the seam will be filled even with the top throughout the length thereof. It is to replace this human element and to replace the uncertainty of the ability of the operator even after a long period of training, with a device of precision which at the same time operates rapidly.

Referring then to the appended drawings, it will be observed that the tucking blade 1 moves in the arc of a circle beneath the feeder 2 through which the oakum O is fed in a continuous strand to the calking iron 3.

The tucking blade 1 has a resilient or yielding mounting on the bridge 4 which connects the tucker arms 5 at the bottom. The tucker arms are pivotally mounted on the pivots 6 which are screwed into the sides of the main frame 7. The construction of the pivotal mounting is shown in Fig. 5. Here it will be observed that the pivot screws 6 have an intermediate bearing portion of a diameter larger than the threaded end and

smaller than the portion adjacent to the heads upon which the tucker springs 8 are coiled. This arrangement of the pivot screws is designed after a well known 5 method, and provides a free mounting of the tucker arms 5, and at the same time, a secure mounting for the pivot screws.

Stops 9 limit the outward movement of the tucking blade 1 under the influence of 10 the springs 8 which are so connected to the tucker arms as to normally retract the tucking blade from the channel 10 in which the calking iron 3 operates. A square slide block 11 occupies the channel 10 and has 15 tucking pins 12 which operate in the opening 13 of each of the bifurcated heads 14 of the tucker arms, during a portion of the stroke of the calking iron. In this connection it will be observed in Fig. 3, that the 20 calking iron is made a part of the slide block 11. Obviously if it be so desired, these adjacent parts may be made separate if practice indicates such to be practicable.

The action of forming the tuck T in Fig. 25 3 is automatically and mechanically performed through the operation of the calking iron 3 on a portion of the return stroke thereof. Fig. 3 just referred to, shows the tucker arms 5 still against the stops 9, and 30 the tucking blade 1 retracted from the channel 10 under the influence of the springs 8. When the upward stroke of the calking iron is nearly completed, the tucking pins 12 will enter the openings 13 between the upper and lower lips 15 and 16 of the head 14, 35 and drive the tucking blade across the channel 10 to form the tuck. Fig. 3 shows the tuck as having been formed, the tucking blade 1 retracted from the channel, and the 40 calking iron 3 in the act of driving the tuck T into the seam S between two planks of a wooden vessel.

Fig. 2 shows the tucking blade 1 in the 45 inner extremity of its movement described in connection with Fig. 3. Fig. 1 shows the same position and also illustrates how the tuck T is initially formed. When the pins 12 leave the openings 13 on the down stroke of the calking iron, the springs 8 force the tucking blade 1 out of the path of the calking iron, and the tucker arms 5 into contact with the stops 9. This action is also assisted initially by the movement of the tucking pins over the lower lip 16.

50 The tucking blade 1 has a transverse flange 17 at the back, which normally rests against the bridge 4 by virtue of the springs 18 on abutment screws 19. The tucking blade 1 is held in place on the bottom of the 55 bridge 4 by means of holding screws 20 which enter slots 21 in the tucking blade. The screws are so adjusted as to hold the tucking blade without excessive freedom so that the sliding function of the tucking 60 blade can be performed.

In this connection attention is directed to Figs. 6 and 7, of which Fig. 7 illustrates the circumstances under which the sliding function of the tucking blade occurs. The tucking blade in Fig. 6 is adjusted to move a 70 distance equal to the width of the channel 10. This distance is approximately three-quarters of an inch. This throw of the tucking blade forms a tuck T of just about the right size to properly fill an ordinary 75 and relatively wide seam S. It has been found in actual practice in the use of this calking tool, that the tension of the oakum strand between the inner edge of the feeder 80 2 and the nearest edge of the seam S, is considerably greater when the seam is relatively narrow.

The increased tension in the oakum strand forms a more rigid abutment as it were, for 85 the edge of the tucking blade, so that instead of permitting the tucking blade to make a full stroke across the channel 10, the tucking action is retarded but is taken up by the compression of the springs 18 on the 90 abutment screws 19 as clearly shown in Fig. 7.

The action just described has been found to work out in actual practice and efficiently takes the place of the manual operations 95 which now customarily must be followed to produce the same result. Thus it may be said that the tucks T are automatically formed of just the right size to fill the seam to the top, regardless of the varying widths of the seam. 100

The remaining calking tool structure although important in its turn, takes the second place when considering the tucking mechanism. The main frame 7 comprises a 105 casing 22 in which a pair of springs 23 and 24 are housed. The outer supporting spring 23 bears against the flange 24a of a cup 25 which is practically a part of the hammer support 26.

A clamp 27 at the top of the hammer support 26, is adapted to secure the calking tool on the end of a mechanically operated hammer of either the type illustrated in my co-pending application for a patent on an electric hammer, filed December 5, 1917, 115 Serial No. 205,503, or any other type. The spring 23 is strong enough to support the weight of the hammer and under normal conditions, presses the shoulder of the cup 25 against the closure cap 28 which is 120 screwed into the threaded end of the casing 22.

Screwed in the cap 28 is a pin 29 which enters the slot 30 in one side of the hammer support 26 and prevents it from turning. 125 A plurality of holes 31 in the base of the slot 30 permit the adjustment of the stop 32 on the hammer support. This stop is for the purpose of gaging the depth to which the calking iron 3 may be forced into the 130

seam S by pressing down on the hammer. The stop 32 has a spring pressed pin 33 which can be pulled out to adjust the stop into the region of any one of the holes.

5 The stem 34 which carries the calking iron at the bottom, has a reduced portion which slides in the bore of the hammer support 26. A pair of nuts 35 are screwed on the threaded end of the stem 34 adjacent to the reduced portion. These nuts occupy the cup 25. The inner spring 24 presses the nuts 35 against the base of the cup and serves to return the calking iron 3 after each stroke of the hammer on the end of the 10 stem 34. In this connection it is to be observed that the upper end of the stem is further reduced to fit in the chuck of the hammer.

Wheels 36 and 37 at the front and rear 20 of the main frame 7 of the calking tool, form a part of the carriage illustrated in Fig. 5. The front wheels have an integral tracking wheel 38. A tracking wheel 39 is separately mounted over a bushing on the 25 axle 40 at the rear of the carriage. Similarly, the wheels 37 are mounted on bushings on the same axle. The front and rear tracking wheels keep the calking tool in alignment with the seam so that the calking 30 iron 3 always strikes in the center.

The operation.

By way of preface it may be stated that such calking devices as for instance those 35 whereby the oakum is gripped by means of a star wheel and fed in by friction against the frame, or a stout spring which grips the material between the feeder and the tool, have been found to be defective in that the 40 oakum strand is readily cut or broken. This necessitates the stopping of the work and the re-threading of the oakum into the machine. As has already been fully explained, the device herein described accomplishes the 45 same result as is accomplished manually.

It is thought unnecessary to repeat in detail, the manner in which the tuck T is formed. It is thought sufficient to say that the springs 18 on the abutment screws 19 50 render the tucking blade 1 sensitive to the varying widths of the seam S, so that the throw of the tucking blade is gaged each time by the width of the seam which is then worked upon. When the seam is narrow as 55 shown in Fig. 7, the tension of the oakum strand between the adjacent edges of the seam and the feeder 2, is greater than when the seam is wide as in Fig. 6, with the result that more resistance to the movement of the 60 calking blade occurs. This increased resistance is taken up in the springs 18.

The modification in Fig. 9 shows a slightly different arrangement of the calking tool. The stem 34 has a reduced and threaded 65 end at the top by means of which the stem

can be screwed directly into the piston 41 of the mechanical hammer. Of course the stem may be connected to the piston by any other suitable means which actual practice may suggest. The hammer support 26 also 70 slides within the casing 22, but instead of two springs inside of the casing, only the supporting spring 23 appears.

The spring 24 abuts a member 35 which is the equivalent of the nuts 25 in Fig. 1. 75 The spring 24 exerts sufficient upward pressure against the buffer 35 to withstand the blows of the piston 41. The remaining structure of the modification is substantially 80 like the structure in Fig. 1 as will be found by a comparison of the reference characters.

The tucking mechanism is also of a slightly modified construction. The tucker arms 5 terminate in lugs 42 beyond the pivots 6, and these lugs coöperate with the tucking pins 12 similarly as the pins 12 coöperate with the heads 14 in Fig. 2. Otherwise, the construction and operation of the tucking mechanism in Fig. 9, is the same as that in the preferred form of the invention. 90

I claim:

1. A calking tool, comprising a calking iron for driving oakum into a seam, and means positively actuated by the engagement of a portion of the calking iron with a 95 part of said means during a portion of the stroke of the calking iron, for automatically forming a tuck beneath said iron crosswise of the seam.

2. In a calking tool, a calking iron for 100 driving oakum into a seam, means positively actuated by the contact of a portion of the calking iron with a part of said means during a portion of the stroke of the calking iron, for automatically forming a tuck 105 beneath said iron, and means for periodically retracting said tuck-forming means from the path of the calking iron.

3. A calking tool, comprising a calking iron for driving oakum into a seam, a tucker 110 including a blade, positively actuated through contact therewith by a portion of the calking iron during a portion of the return stroke of the iron, thereby thrusting the blade beneath the iron and automatically 115 forming a tuck in the oakum strand across the seam; and means coöperating with the tucker-blade for automatically regulating the size of the tuck in accordance with the varying widths of the seam. 120

4. In a calking tool, a calking iron for 125 driving oakum into a seam, means pivoted adjacent to the calking iron and movable across the ends of the calking iron to form a tuck in a strand of oakum, means embodied in said tuck-forming means having a yielding action sensitive to various degrees of tension in said strand caused by varying widths of the seam, thereby forming tucks of various sizes, and means extend- 130

ing from the tuck-forming means into the path of a portion of the calking iron, arranged to be engaged during a portion of the return stroke of the iron to actuate said 5 tuck-forming means.

5. In a calking tool, a calking iron for driving oakum into a seam, means pivoted adjacent to the calking iron and movable across the end of the calking iron to form 10 a tuck in a strand of oakum, means embodied in said tuck-forming means having a yielding action sensitive to various degrees of tension in said strand caused by varying widths of the seam, thereby forming tucks 15 of various sizes, means extending from the tuck-forming means into the path of a portion of the calking iron, arranged to be engaged during a portion of the return stroke of the iron to actuate said tuck-forming 20 means, and resilient means for holding said tuck-forming means out of the path of the calking iron during the calking stroke and during the period of disengagement between said extending means and the co-operating portion of the calking iron. 25

6. In a calking tool, a calking iron for driving oakum into a seam, tuck-forming means co-operating with the iron and positively actuated thereby, resilient means for 30 holding the tuck-forming means in a retracted position, and stops for limiting the influence of said resilient means and enabling the independent holding of said tuck forming means during the operation of driving the calking iron into a deep seam. 35

7. A calking tool, comprising a wheeled main frame, a calking iron reciprocatively mounted therein for driving oakum into a seam, a tuck-forming mechanism for forming a tuck in a strand of oakum beneath the calking iron after each return stroke of said iron, mounted and operating laterally of the main frame, and a laterally disposed oakum feeder above said tuck-forming mechanism. 40

45. 8. A calking tool, comprising means for forming tucks of a size to accord with varying seam widths, consisting of a calking iron, pivotally mounted tucker arms including a bridge, an engageable portion beyond the pivots, tucking pins on the calking iron for engaging said portions to drive said arms inwardly, a tucking blade with a flange, means providing a limited movement of the tucking blade on the bridge, an oakum feeder, 50 and abutments with interposed resilient means coacting with the tucking blade flange and enabling a retrograde movement of the tucking blade on the bridge, to compensate for an increase in resistance in an oakum 55 strand of increased tension, between the feeder and a narrow seam. 60

9. In a calking tool, a main frame having a channel and a casing, a stem having a calking iron occupying the channel and provided with a non-circular slide block, tuck- 65

ing pins carried by the slide block, a pivotally mounted tuck-forming mechanism actuated by said tucking pins on the return stroke and operating beneath the calking iron, a resilient stem support in the casing 40 for returning the calking iron to the normal position, a hammer support adapted to be clamped to a mechanical hammer for securing the calking tool to said hammer, a cup included in said hammer support 75 occupying a position in said casing, an abutment carried by the stem and occupying the cup, and a resilient support contacting the cup and upholding the hammer support. 75

10. A calking tool, comprising a main 80 frame and a casing, a hammer support telescopically mounted in the casing, resilient means concealed in the casing and holding the hammer support up, means included in the hammer support for attaching the calking tool to a mechanical hammer to constitute the calking tool as an attachment thereto, and stopping means on the hammer support, arranged to engage the top of the casing and limit the downward thrust of 90 the hammer support through pressure on the hammer. 90

11. In a calking tool, a main frame having a channel and a casing, a stem having a calking iron occupying the channel and provided with the non-circular slide block, tucking pins carried by the slide block, a pivotally mounted tuck-forming mechanism actuated by said tucking pins on the return stroke and operating beneath the calking 100 iron, a hammer support including an abutment member occupying the casing, a resilient support therefor, an abutment member carried by the stem and occupying a position in a portion of the hammer support, 95 and a resilient support between said abutment member and the abutment member in 105 said casing. 105

12. A calking tool, comprising a main 110 frame and a casing, a hammer support telescopically mounted in the casing, resilient means concealed in the casing and holding the hammer support up, means included in the hammer support for attaching the calking tool to a mechanical hammer to constitute the calking tool as an attachment there- 115 to, stopping means on the hammer support, arranged to engage the top of the casing and limit the downward thrust of the hammer support through pressure on the hammer, a calking iron having a stem extending through the casing and hammer support to the hammer, and means providing a resilient support for the stem to act as a resilient support for the stem to absorb the shocks of the 120 blows of the hammer. 125

13. A calking tool, comprising a calking iron for driving oakum into a seam, means positively actuated by the contact of the portion of the calking iron with a part of 130

5 said means during a portion of the stroke of the calking iron for automatically forming a tuck beneath said iron, and means for automatically withdrawing said tuck-forming means out of the path of the calking iron when said positive actuating contact is severed.

10 14. Instrumentalities embodied in a calking tool for automatically forming tucks in a strand of calking material across a seam of increasing or diminishing sizes to correspond to the increase and decrease in the width of the seam; comprising a calking iron; and a swinging tucker, comprising a portion engageable by a part of the calking iron near the end of the return stroke to swing the tucker, and a tuck-making portion arranged to yield on engaging the calking material when it is under tension; as in 15 calking a narrow seam and not to yield on engaging the calking material when it is loose as in calking a wide seam.

20 15. A swinging tucker for a calking tool, comprising a tuck-forming blade mounted on a tucker; and resilient means forming a part of said mounting, enabling the blade to yield and recede when presented a stiff oakum strand thus forming a small tuck, and holding the blade immovable on the tucker when presented to a loose oakum strand thus forming a large tuck.

25 16. In a calking tool, the combination of a frame provided with means to guide calking material to a seam, a reciprocative tuck-forming blade for forming tucks in said material, means for supporting and guiding said blade to cause a bodily edgewise movement thereof, and means operative to reciprocate said blade.

30 40 17. In a calking tool, the combination of a frame provided with means to guide calking material to a seam, a reciprocative calking element for driving said material into a seam, a reciprocative tucking blade for 45 forming tucks in said material, means for supporting and guiding said blade to cause a bodily edgewise movement thereof, and means controlled by said element during the operation thereof for reciprocating said 50 blade.

55 18. In a calking tool, the combination of

a frame provided with means to guide calking material to a seam, a pivoted reciprocative member, a tucking blade carried by said member and moved edgewise thereby when said member is moved for forming tucks in said material, and means operative to reciprocate said member.

60 19. In a calking tool, the combination of a frame provided with means to guide calking material to a seam, a reciprocative calking element for driving said material into a seam, a pivoted reciprocative member, a tucking blade carried by said member and moved edgewise thereby when said member 65 is moved for forming tucks in said material, and means controlled by said element during the operation thereof for reciprocating said member.

70 20. In a calking tool, the combination of a frame provided with means to guide calking material to a seam, a reciprocative member, a yielding tucking blade carried by said member for forming tucks in said material, and means operative to reciprocate 75 said member, said blade being adapted to yield relatively to said member under a predetermined pressure against said material during the tucking operation.

75 21. In a calking tool, the combination of a frame provided with means to guide calking material to a seam, a reciprocative calking element for driving said material into a seam, a reciprocative member, a yielding tucking blade carried by said member for 85 forming tucks in said material, and means controlled by said element during the operation thereof for reciprocating said member, said blade being adapted to yield relatively to said member under a predetermined pressure against said material during 90 the tucking operation.

95 22. In a calking tool, the combination of a frame provided with means to guide calking material to a seam, a movable tucking device having a yielding part adapted to form tucks in said material, and means operative to move said member, said part being adapted to yield under a predetermined pressure against said material during the 100 tucking operation.

LOUIS PAULERO.
